UNITED STATES PATENT OFFICE.

WILLIAM A. WHITMIRE, OF BIG CREEK, CALIFORNIA.

EXCAVATING APPARATUS.

Application filed March 13, 1923, Serial No. 624,864. Renewed September 25, 1926.

My invention relates to that class of excavating apparatus commonly known as "mucking" machines, and more particularly to an apparatus especially designed for excavating earth from shallow and narrow tunnels, and having associated therewith suitable mechanism for delivering the excavated material to "dump cars" for transportation.

10 In the excavation of tunnels, designed for hydraulic flawlins, transportation, and for other purposes, where little head room is desired or needed, excavating apparatus of the usual design cannot be economically utilized, owing to its structural design, as the earth removing "dipper" of such machines usually requires excessive "head room" for successful operation, as well as sufficient width so as to enable the mechanism to deliver the excavated material to the rear or side of the apparatus for convenient removal.

It is an object of my present invention to provide an excavating apparatus that will 25 efficiently and economically operate in tunnels or bores of comparatively small cross sectional dimensions.

Another object of my invention is to provide a mechanism in which the material 30 removing means is utilized to transport and deliver the excavated material to dump cars directly to the rear or side of the apparatus.

A further object of my invention is to 35 provide a mechanism in which the excavating dipper performs the dual function of excavating the material and conveying or transporting the same to the rear of the apparatus, the dipper or scoop when conveying the material being disconnected from the 40 excavating mechanism and performing the functions of a dump car.

The above and other objects of my invention will be more fully disclosed in the following specification, reference being had to 45 the accompanying drawings, in which:

Fig. 1 is a side elevation of the front section of my apparatus.

Fig. 1^A is a side elevation of the middle section of the same.

50 Fig. 1^B is a side elevation of the rear section of the same.

Fig. 2 is a plan view of the front section of the apparatus.

Fig. 2^A is a plan view of the middle section of the apparatus. 55

Fig. 2^B is a plan view of the rear section of the apparatus.

Fig. 3 is a transverse section taken on the line 3—3 of Fig. 1 viewed in the direction indicated by the arrows. 60

Fig. 4 is a fragmental plan section taken approximately on the line 4—4 of Fig. 3.

By the above description of the figures of the drawings, it will be observed that Figs. 1, 1^A, and 1^B, when placed together constitute the entire side elevation of the apparatus, and Figs. 2, 2^A, and 2^B, when placed together constitute the entire plan view of the apparatus. It was found necessary to divide the views in this manner, due to the 70 comparative great length of the apparatus with its height and width, and in order to bring out clearly the details of construction in a comprehensive manner.

In carrying out my invention 75 5 represents a base comprising a truck of any desired construction adapted to be propelled on rails secured to the tunnel floor, 6 a swinging body structure mounted above the truck 5 and pivoted at 7 thereto intermediate its ends, 80 8 a carriage frame mounted on the structural body 6 and adapted for longitudinal movement thereon, 9 a digging and conveying dipper adapted to excavate the earth and transport and dump it to the rear of the 85 apparatus, and 11 a ram adapted to force the dipper forward to scoop up the earth and also to move the carriage frame 8 to which it is secured.

The truck 5 comprises a platform 12 90 preferably formed of sheet metal and suitably braced by structural steel and supported thereby on the forward wheels 13 and the rear wheels 14, said wheels being propelled when desired through the medium of 95 sprocket chains 15 and 16 which engage with sprocket wheels 17 and 18 secured to the wheel shafts, and the sprocket wheels 19 and 20 secured to a transversely disposed shaft 21 journaled in bearings 22 secured to 100 the truck frame.

The shaft 21 is provided with a worm gear 23 adapted to mesh with a worm 24 secured to one end of a shaft 25 journaled in a bearing 26 which in turn is secured to the truck 105 frame. Journaled loosely on the shaft 25

is a worm gear 27 which meshes with a worm 28 secured to the crank shaft 29 of an engine 30 which is firmly secured to the truck frame and which preferably has compressed air for a motive power. The worm gear 27 may be keyed to the shaft 25 to revolve the same when it is desired to move the truck along the rails, by means of a clutch mechanism 31, which comprises a slidable clutch 10 collar 32, adapted to rotate with shaft 25 and to be slid thereon by means of the lever 33, to engage with the clutch member 34 secured to worm wheel 27.

The body structure 6 comprises a bottom plate 35 to which is secured, adjacent its forward end, a transversely disposed casting 36 having journaled thereon a plurality of rollers 37 adapted to roll upon a plate 38 secured to the truck 5, and it also has secured to it intermediate its ends a turn table 39, through which the king bolt 7 passes, which rests upon a plate 40 secured to truck 5. By this construction it will be obvious that the body 6 may be pivotally swung on the truck, the forward end thereof being anti-frictionally supported on said truck, and in order that this swinging movement may be conveniently accomplished, the following mechanism is employed.

30 The crank shaft 29 of engine 30 is provided with a pinion 41 which is loosely journaled thereon and meshes with a gear 42 secured to a shaft 43 journaled in bearings 44 secured to the truck 5, the pinion 41 being, at the will of the operator, locked in engagement with the crank shaft 29 by means of a well known clutch mechanism 45 controlled by a lever 46.

Secured to the shaft 43 is a drum 47 around which is wound, in opposite directions, the cables 48 and 49 which pass around sheaves 50 and 51 journaled on truck 5, and have their free ends secured at 52 and 53 to the casting 36 of body 6. By this arrangement it will be obvious that when the engine crank shaft 29 is geared to the drum by means of the clutch mechanism 45 the body 6 will be caused to swing on the pivot 7, the direction of swing being controlled in the usual manner, by reversing the direction of the engine.

Extending upwardly from the bottom 35 of body 6 are the oppositely disposed side plates 55 to which are secured the oppositely and longitudinally disposed angle irons 56, 57, and 58, the top angle iron 58 having secured thereto the rails 59.

60 The frame 8 comprises a platform 60, preferably formed of boiler plate, re-enforced by means of the transversely disposed bars 61 which are spaced apart throughout its length, and journaled on the ends of said bars are the rollers 62 which ride on the rails 59 of the body member 6, and thereby support the frame and also permits of its

having longitudinal movement thereon. Secured to the upper surface of platform 60 are the oppositely and longitudinally disposed angle irons 63 adapted to serve as rails upon which the dipper 9 is adapted to ride during its carrying function.

Secured to the under surfaces of the bars 61 are the oppositely and longitudinally disposed angle irons 64 to which are secured the downwardly projecting side plates 65, which have secured to their lower extremities the angle irons 66 which support a transverse shaft 67 having journaled on its ends rollers 68 which run on the angle irons 56, thus providing an additional support for the heavy frame 6.

Fastened to and in between the angle irons 64 and 66 of the frame 6 are the forwardly extending oppositely disposed blocks 70 having secured therebetween a shaft 71 which is held against revolution, and journaled on this shaft is a dipper elevating crane comprising a segmental rack 72, which is split in its center, as clearly shown in Fig. 2 of the drawings, to form a passage therebetween for the admission of a cable, the purpose of which will hereinafter be described. The rack segments are provided with downwardly projecting flanges 74 and are joined together by means of a plate 75 which is secured to these flanges.

Journalized in bearing blocks 76 (see Fig. 3), secured between angle irons 64 and 66 is a shaft 77 to which is keyed the pinions 78 which mesh with the segmental gears 72, and also secured to the shaft are the gears 79 which mesh with pinions 80 secured to the shaft 81 journaled in the bearing blocks 76. Secured to shaft 81 is a gear 82 which meshes with a pinion 83 secured to a shaft 84 journaled also in the bearing blocks 76. Secured to shaft 84 are the balance wheels 85 to which the pitmen 86 are connected, said pitmen being connected to the cross heads 87 of an engine 88 mounted on a transverse channel iron 89 secured to the angle irons 63 of frame 6.

The train of gears above described are intended to provide a suitable leverage between the engine 88 and the segmental gears 72, and to rock the segments on the pivots 71, when the engine is started, to dispose them in the position shown in dotted lines in Fig. 1 of the drawings, and thereby elevate the dipper 9 and dispose it in a horizontal position to register with the angle iron tracks 63.

The entire frame 6 is adapted to be moved longitudinally forwardly and backwardly on the body 5 by means of an engine 90, mounted on said body, through the medium of leverage gearing, which comprises a shaft 91 journaled in the frame of engine 90 and having secured thereto the pinions 92 which mesh with the teeth of a rack bar ram 92

secured at one of its ends to a cross bar 94 of frame 6. Keyed to shaft 91 are the gears 95 which mesh with pinions 96 secured to a shaft 97 journaled in bearings formed on the frame of engine 90. Secured to shaft 97 are the balance wheels 98 which are connected to the cross heads 99 of engine 90 by means of the pitmen 100. It will be obvious that by the above recited mechanism the frame 6 carrying the segmental gears 72 and rails 63 may be moved backwardly and forwardly at the will of the engineer.

Secured to the plate 75 of segmental racks 72 are the oppositely disposed channel irons 101 which serve as rails for the wheels 102 of the dipper 9, and are adapted to register with the rails 63 when the dipper is elevated by means of said racks.

The dipper 9 is of the usual construction, it being provided with the dipper teeth 103 and the dump gate 104, which is hinged to a rod 105 secured between ears 106 secured to the side walls of the dipper. A bar 107 extends between the ears 106, and centrally disposed thereon is a bumper knob 108. The gate 104 is held normally closed by means of the spring pressed latches 109 pivoted to the sides of the dipper and adapted to engage with the outwardly projecting ends of a bar 110 secured to the gate as more clearly shown in Figs. 1 and 2 of the drawings.

The ends of oppositely disposed cables 112 are secured to pins 113 projecting from the sides of the dipper 9, and these cables pass over sheaves 114, journaled on the outwardly projecting ends of the shaft 71 secured to the oppositely disposed blocks 70, and from thence extend rearwardly and pass over sheaves 115 journaled on upright angle irons 116 secured to the rear of the frame 6, and from thence over the sheaves 117 also journaled on said frame, and then forwardly under the rails 63 of the frame. The opposite ends of these cables are then wound around drums 118, secured to the ends of a shaft 119 extending from and driven by a pair of rotary compressed air motors 120 and 121 which are secured to a channel iron 122 secured to the platform 60 of frame 6.

Another cable 123, having one of its ends secured at 124 to the bottom of the dipper midway between its sides, passes over sheaves 125, 126, and 127 journaled on the segmental racks 72 and then over suitable sheaves 128, 129, 130 and 131 and the opposite end is then wound around a drum 132 secured to the motor shaft 119. The sheave 130 is mounted on a swinging arm 133 so as to provide means for taking up the slack in the cable.

At the rear end of the frame 6 the tracks 63 are provided with depressions 134 for the reception of the dipper wheels 102 during a dumping operation, and also extend-

ing transversely across the frame are the bars 135 and 136, the bar 135 being adapted to engage with the dipper latch 109 to disengage it from the bar 110 and thereby permitting the gate 104 to open, and the bar 136 being provided with a stop button 137 adapted to engage with the bumper button 108 of the dipper as clearly shown in dotted lines in Fig. 1^B of the drawings.

In the operation of the apparatus, the dipper 9 is pushed forward to scoop up the dirt by means of the engine 90 which is coupled to the ram 11 through the leverage gearing previously described. At this time the entire frame 6 and mechanism secured thereto also moves forward. When the dipper is filled, the engine 88 is started which through the intermediate gearing causes the segmental gears to rotate on the shaft 71, thus elevating the dipper and tracks 101 to the position shown in heavy dotted lines, (see Fig. 1). At this time the tracks 101 register with the tracks 63.

The motor 120 (see Fig. 2^A) is then started in motion which causes the drums 118 to rotate to wind up the cables 112 and thus draw the loaded dipper rearwardly, over the tracks 63, the motor 121 running idle at this time and the cable 123 paying off the drum 132.

When the dipper reaches the rear end of the frame 6 the forward wheels thereof drop into the depressions 132 of tracks 63, and upon continued pull on the cables 112 the dipper is caused to tilt, with the forward wheels as a pivot, until the bumper 108 contacts with the stop button 137, and at the same time the free ends of the latches 109 strike against the bar 135 and are consequently disengaged from the gate bar 110, whereupon the dirt in the dipper presses against the gate and opens the same, thus permitting the dirt to fall from the dipper into the dump car 10 disposed under the dipper.

After the dirt has been dumped from the dipper as above described the motor 121 is operated to revolve the drum 132 in an opposite direction to that which the drums 120 and 121 were previously operated, thus creating a forward pull on the cable 123 and consequently drawing the dipper forward, the motor 120 running idle during this operation.

After the dipper has ridden on the tracks 101, the engine 87 is operated to return the segmental gears and the parts carried thereby to their normal positions, whereupon the excavating and dumping operations may be repeated.

When it is desired to excavate the earth from the sides of the tunnel, the swivel mechanism comprising the drum 47 and cables 48 and 49, may be thrown into gear with the engine 30, by means of the lever 46

and clutch mechanism controlled thereby, and thus the entire frame and mechanism supported thereon may be turned on the pivot 7 at any desired angle with respect to the truck 5.

By the employment of the apparatus above described it will be obvious that the earth may be excavated from the tunnel in front of the truck, at different levels, the dipper being moved upwardly or downwardly on the tracks 101 to accomplish this, or it may be excavated from either side of the tunnel when a wide tunnel is desired. It will also be obvious that one or more dump cars may follow the truck, disposed directly behind or on either or both sides of the same.

It will also be noted, that by the construction described, the apparatus may be operated in tunnels having limited head room and of narrow width, due to the fact that no long dipper booms, sticks or lever bars are employed, and that the dipper is moved to the rear of the apparatus on substantially the same level throughout its travel and directly above the apparatus which is comparatively short in height.

Although I have described each of the various steps of the apparatus as following one after the other, it will be apparent that at the discretion of the operator, these steps may overlap one another and thereby obviate all waste of time in the operation.

It will be observed that the platform plates 35 and 60 and the side plates 55 and 64 not only serve as structural features but also serve as housing walls to protect the working parts of the apparatus from the excavated material which is being handled.

What I claim is—

40 1. An excavating apparatus, comprising a wheeled truck, an excavating mechanism supporting body pivotally mounted on said truck, a carriage frame supported for longitudinal movement on said body, an elevating crane pivoted to said carriage frame, and a dipper mounted for movement on said carriage frame and elevating crane.

45 2. An excavating apparatus, comprising a wheeled truck, a body provided with rails pivoted intermediate its ends to said truck, a carriage frame provided with wheels adapted to run on the rails of said body and having rails mounted thereon, a dipper

elevating crane provided with rails adapted to register with the rails of said carriage frame and pivoted on said carriage frame, a digging and conveying dipper provided with wheels adapted to run over the rails of said frame and crane, and means for independently operating said truck, body, frame, crane, and dipper.

3. An excavating apparatus, comprising a wheeled truck, means for propelling said truck, an excavating mechanism supporting body pivoted on said truck intermediate its ends, motive means for swinging said body on its pivot, a digging and conveying dipper supporting carriage frame movably mounted on said body, means for reciprocating said frame on said body, a segmental rack pivoted on said frame, means for operating said segmental rack, a digging and conveying dipper mounted for reciprocal movement on said frame and segmental rack, and means for operating said dipper.

4. An excavating apparatus, comprising a wheeled truck, a digging and conveying dipper elevating crane mounted for reciprocating and rocking movements on said wheeled truck, a digging and conveying dipper cooperating with said wheeled truck and crane, means for operating said crane, and means for moving said dipper on said wheeled truck and crane.

5. An excavating apparatus, comprising a wheeled truck, a digging and conveying dipper elevating crane mounted for reciprocating and rocking movements on said wheeled truck, an engine mounted on said wheeled truck, leverage gearing interposed between said engine and said crane for reciprocating the same, an engine mounted on said crane, leverage gearing interposed between said second mentioned engine and crane for rocking the same, a digging and conveying dipper cooperating with said wheeled truck and crane, a motor mounted to reciprocate with said crane, and cables interposed between said motor and dipper for moving the same on said crane and wheeled truck.

In witness that I claim the foregoing I have hereunto subscribed my name this sixth day of February, 1923.

WILLIAM A. WHITMIRE.
